CLAIM

The ornamental design for the handle of an electric grill, as shown and described.

DESCRIPTION

FIG. 1 is an elevated isometric view of an embodiment of a handle for an electric grill showing the new design;
FIG. 2 is a front view of the handle for an electric grill shown in FIG. 1;
FIG. 3 is a rear view of the handle for an electric grill shown in FIG. 1;
FIG. 4 is a left side view of the handle for an electric grill shown in FIG. 1;
FIG. 5 is a right side view of the handle of an electric grill shown in FIG. 1;
FIG. 6 is a top view of the handle of an electric grill shown in FIG. 1; and,
FIG. 7 is a bottom side view of the handle of an electric grill shown in FIG. 1.

The broken lines shown in the appended figures are for purposes of illustrating environmental structures and form no part of the claimed design.
